METHOD OF FORMING ARTIFICIAL TEETH

Henry M. Thornton, York, Pa., assignor to The
Dentists' Supply Company of New York, New
York, N. Y., a corporation of New York

Application May 3, 1941, Serial No. 291,687

3 Claims. (Cl. 18—55.1)

This invention relates to artificial teeth and methods of forming the same from plastic material.

Heretofore, it has been common practice to make artificial teeth from relatively high fusing porcelain materials, wherein the tooth is formed in a multi-part mould, and subsequently fired at a temperature, such as 2000° F. or higher, to vitrify the porcelain materials.

Plastic material, as contemplated herein, includes materials which will flow under high pressure and relatively low temperature compared to the fusing temperature of porcelain, and which will be substantially immediately hardened after introduction into the mould. Suitable plastic materials which may be employed are acrylics, styrenes, vinyls, phenolic resins and similar plastics. "Plastic materials" as used herein is intended to cover not only thermo-plastic materials but suitable thermo-setting materials.

It is an object of my invention to provide improved methods of forming articles, such as artificial teeth, of plastic material.

Another object of my invention is to provide a method of forming artificial teeth which, in many instances, can be readily united with a denture base or plate without the use of a mechanical anchorage.

Another object of my invention is to provide a method of forming artificial teeth hardenable at relatively low temperatures, whereby numerous coloring materials impractical for high fusing porcelain teeth may be used.

Another object of my invention is to provide a method of forming artificial teeth of the above type which closely simulate natural teeth in appearance.

One method of practicing the invention is to provide a two-piece mould generally similar to moulds heretofore employed in forming porcelain teeth, but which is provided with a main gate in the mould and smaller gates extending from the main gate into individual tooth pockets. Plastic material of a desired viscosity is then forced under relatively high pressure through the gates into the mould and individual pockets.

Injection moulding machines are well known, and any suitable machine may be employed for forcing the material into the mould. In this method only one material is employed, and by taking advantage of the variations in thickness of the tooth labially-lingually from the gingival third to the incisal third, and/or the surface contours of the tooth, variations in translucency and color effect may be provided simulating a natural

tooth in appearance. Under both reflected and transmitted light, many plastics have an optical similarity to the dentine and enamel of natural teeth. Because of this fact the tooth surfaces, and particularly the labial surface, can be arranged to simulate natural teeth even though only one material is used. Additionally, slight irregularities may be provided at the labial surface of the tooth to create various effects of shading.

10 To further simulate the appearance of natural teeth and create a more definite and natural blend between the incisal and gingival portion of the tooth, material of any suitable composition, organic or inorganic, such as glass fiber, glass cloth, metal, wood, plastic or porcelain pieces, or similar materials, of any color and of any degree of opacity or translucency may be placed in the individual tooth pockets of the mould. The mould is then closed and the plastic material injected. The deposited material will then become incorporated in the tooth and the deposited material can be initially shaped to give the tooth an appearance of being formed of body and enamel materials blended in a natural manner. 15 It is apparent that the shape and substance of this incorporated material is unlimited, and it may be shaped to form stripes, lobes, spots and the like, as well as to vary the translucence, opacity, or color in different portions of the tooth.

20 A second method of practicing the invention is to form the teeth in two stages. Either the body portion or the enamel may be formed as the first stage. If the enamel or veneer is first formed, a mould part conforming to the labial contour of the veneer is used in cooperation with a shader mould part conforming to the lingual contour of the veneer, so that when the mould parts are engaged a mould cavity corresponding in size and shape to the enamel or veneer is formed therebetween. Plastic material is then 25 injected into the mould cavity under high pressure and the mould parts are subsequently separated so that the moulded veneer remains in the labial forming mould part. The body forming mould part then replaces the shader mould part on the injection machine and is engaged with the labial forming mould part, thereby 30 providing a cavity between the lingual portion of the veneer and the body-forming mould part, which will conform to the size and shape of the body portion of the tooth. Body-forming plastic material is then injected into said cavity under high pressure, and after separating the mould parts, the moulded tooth is removed. Thus, by 35 the use of suitable plastic material both for the

veneer and for the body portion, a color blending may be effected similar to that heretofore achieved in porcelain. Of course, the body portion may be first formed, if desired, and organic or inorganic colored material may be incorporated in the tooth, as described in connection with the first method of moulding wherein a two-piece mould was employed and only one plastic material was used to form the teeth. The composition of the plastic material of the veneer portion and of the body portion may be the same, except for the amount of coloring and/or opacifying agents employed. Also, the enamel may be formed of one plastic material and the body portion of a different plastic material which is compatible with the veneer as to bonding qualities. For example, in the first instance, both the veneer and body material may be formed of acrylics, and in the second instance, the veneer may be formed of an acrylic and the body of a styrene.

A third method which I may employ is to inject plastic material into a mould cavity conforming to the enamel or veneer, and also to inject plastic material into a separate mould cavity conforming to the body portion of the tooth. These two separately formed parts may then be securely united by painting or spraying a solvent or cement, for the particular plastic material or materials used, over the lingual side of the veneer portion, or the labial side of the body portion, or both, and quickly pressing the parts together in proper position.

It is further contemplated that a solvent or cement may be applied at the completion of the first stage, in the two-stage method, to the exposed surface of the part which is first formed. Also, to insure perfect adhesion, supplemental heat may be applied to the first formed part just prior to the second injection in the two-stage method.

The drawings illustrate embodiments of the invention and the views therein are as follows:

Figure 1 is a plan view of a mould part having labial tooth forming depressions therein.

Figure 2 is a plan view of a mould part adapted to cooperate with the mould part of Figure 1, having lingual tooth forming depressions therein.

Figure 3 is a fragmentary sectional view with the mould parts of Figures 1 and 2 engaged taken along the line 3-3 of Figure 2.

Figure 4 is a fragmentary sectional view with the mould parts of Figures 1 and 2 engaged taken along the line 4-4 of Figure 2.

Figure 5 is a plan view of a moulded unit formed by employing the mould parts illustrated in Figures 1 and 2.

Figure 6 is a diagrammatic view of an injection moulding machine which I may employ.

Figures 7 and 8 are plan views of cooperating mould parts adapted to form the body portions of the teeth.

Figure 9 is a plan view of a moulded unit formed by the mould parts of Figures 7 and 8.

Figure 10 is a plan view of the moulded unit of Figure 9 after veneer has been moulded to the body portions of the teeth.

Figure 11 is a fragmentary section showing the mould parts of Figures 7 and 8 engaged taken along the lines 11-11 of Figures 7 and 8.

Figures 12 is a plan view of a mould part having depressions therein for forming the lingual surfaces of the teeth.

Figures 13 is a fragmentary section showing

the mould parts of Figures 1 and 12 engaged, taken along the line 13-13 of Figure 12.

Figure 14 is a fragmentary sectional view showing the manner of providing a mechanical anchorage in a tooth.

Figure 15 is a rear elevational view of a finished tooth showing outlines on the tooth lingual surface to which the tooth may be ground to alter the shape thereof.

Figure 16 is a front elevational view of a finished tooth, and

Figure 17 is a section taken on the line 17-17 of Figure 16.

Referring now to the drawings, and particularly Figure 6, I have indicated an injection moulding machine generally at 10. Injection moulding machines are well known, and any suitable type may be used, and the mould parts may be disposed to engage either horizontally or vertically. In the present instance, the moulding machine is illustrated largely diagrammatically and the mould parts are disposed to engage horizontally. A supply pipe 11 extends from a supply hopper (not shown) to discharge material into a cylinder 12. A ram 13 operates within cylinder 12 and may be actuated hydraulically to exert relatively high pressure, such as 30,000 lbs. per square inch. Cylinder 12 communicates with a press head 14 having a generally conical opening 16 therein. A generally cylindrical nozzle 17 communicating with opening 16 extends outwardly from the face of press head 14. Secured to the press head in any suitable manner, or formed integrally therewith as shown, is a generally box-shaped mould housing 18. A mould part 19 is mounted within and detachably secured to housing 18 by bolts or the like.

A clamping ram 21 is adapted to be moved axially by any suitable means, such as hydraulic pressure, and is provided with a cooperating mould housing 22. Detachably mounted within housing 22 is a second mould part 23 adapted to be maintained in pressure engagement with mould part 19 by clamping ram 21.

The mould parts are illustrated in detail in Figures 1 to 4, inclusive. Mould part 19 has a surface 24 substantially flush with the peripheral portions of housing 18, and generally centrally of the mould part is a slightly elevated surface 26 having depressions 27 formed therein. Depressions 27 are adapted to form the labial portion of a tooth, and may be provided with slight irregularities, such as elevations, to form corresponding irregularities in the labial surface of the finished tooth.

Mould part 23 is provided with a surface 28 substantially flush with the peripheral portions of housing 22. A slightly concave surface 29 is provided generally centrally of mould part 23 within which are formed depressions 31 adapted to form the lingual portions of the teeth. A generally U-shape main gate 32 is provided in mould part 23, and smaller gates 33 afford communication between the main gate and the depressions 31. Pins 25 adapted to be received in holes 26 may be provided for maintaining the mold parts in proper alignment in engaged position.

As best indicated in Figure 3, nozzle 17 extends through mould part 19 to communicate with main gate 32. Spaced holes 34 are provided in main gate 32 for receiving knock-out pins 35, and each of the depressions 31 is provided with a hole 36 for receiving knock-out pins 37. Mould part 23 has a hole 38 therethrough adapted to receive a knock-out pin 39. The upper portion

of hole 38, as indicated at 41, is of enlarged undercut form.

Single stage method

The manner of forming artificial teeth of only one plastic material, and in a single stage will now be described:

A desired quantity of plastic material, preferably in granular or powdered form, will be discharged into cylinder 12 from supply conduit 11 after retracting ram 13 to uncover conduit 11. The material in the forward portion of cylinder 12 is preferably heated, as by resistance coils 42, so that this material is in a plastic and/or semi-plastic state. The knock-out pins are arranged as illustrated in Figures 3 and 4, and are carried forwardly with clamping ram 21 as it advances to engage the mould parts 19 and 23, whereby the surfaces 24 and 26 of mould part 19 will be in mating contact with surfaces 28 and 29 of mould part 23. Of course, sufficient pressure will be applied to clamping ram 21 to maintain the mould parts in sealing engagement during the moulding operation. Cylinder ram 13 will then be moved forwardly under relatively high pressure to discharge a desired amount of material through nozzle 17, gates 32 and 38, into the tooth cavities 43 formed between the engaged mould parts. Due to the high pressure under which the material is injected, it reaches all of the tooth cavities substantially instantaneously. Thus, a material which hardens quickly, and at a relatively low temperature can be used. The moulded teeth are indicated at 44, and after the moulding operation, which requires only a short interval, the mould parts are separated by withdrawing clamping ram 21, and the material which has been forced into undercut portion 41 of mould part 23 insures that the moulded unit 46 will remain in mould part 23.

When ram 21 is reversed to disengage mould parts 19 and 23 the plastic material extending from nozzle 17 to main gate 32 is extracted from the nozzle by undercut 41 in mould part 23. The knock-out pins may be attached to a plate 47, and this plate may be withdrawn a predetermined distance with clamping ram 21, and then held in a fixed position while the clamping ram continues to retreat, and thus, projecting the knock-out pins forwardly into main gate 32, depressions 31, and hole 38 to force the moulded unit from mould part 23. The knock-out pins will subsequently be withdrawn to the position shown in Figures 3 and 4, and the cycle of operations will be repeated.

I have found that even though only one plastic material is employed in the above described process, that the optical similarity of plastics in artificial teeth to natural teeth under both reflected and transmitted light, and the tapering of the teeth labially-lingually from the gingival third to the incisal edge will create a natural effect of shading and translucency. Also, irregularities may be provided on the labial surface of the moulded tooth by suitably shaping the labial forming depressions 27 of mould part 19, which will enhance the effect of shading and translucency.

Further, I contemplate that any desired surface irregularities may be provided on the tooth subsequent to the moulding operation, since plastic materials are considerably easier than porcelain to shape by grinding or the like. Due to the ease with which teeth of this type may be shaped, I may provide one or more outlines on the lingual

surface of the moulded tooth as a guide to the dentist in shaping the tooth to whichever outline he may desire, for example, square, tapering or ovoid. Thus, a single tooth will provide a choice of two or more contours and the tooth can be shaped to a desired contour by grinding to the outline. This effects a considerable reduction in the number of tooth sizes and forms necessary.

Figure 15 illustrates a rear elevational view of a finished tooth having the gingival two-thirds thereof of generally square outline, as indicated at 48. A tapering outline 49a, indicated in dotted lines, may be provided on the lingual surface in any suitable manner as by providing corresponding ridges or grooves in depressions 31 of back mould part 23. If ridges are provided, the outline 49a will appear on the finished tooth in the form of depressed lines, and if grooves are provided in depressions 31, the outline will appear on the finished tooth in the form of ribbed lines. Of course, these outlines may be marked on the tooth by a suitable instrument subsequent to the moulding operation, if desired. I have indicated at 45 an outline of generally ovoid form. To further improve on shading and naturalness, and create a more definite and natural blend between the incisal and gingival portions of the teeth, material of any suitable composition, organic or inorganic, may be placed in the individual tooth cavities or pockets of the mould prior to engaging the mould parts. After the plastic material is injected this material will be incorporated in the moulded tooth, and since the plastic material hardens at a relatively low temperature, as compared to the fusing temperature of porcelain teeth, a wide variety of materials may be employed which would be impractical in porcelain teeth. For example, glass fiber, glass cloth, metal, wood, plastic or porcelain pieces, or many other compositions of various colors and opacities may be used. This material may have any desired degree of opacity and can be so shaped initially to give the finished tooth the appearance of being made of body and enamel materials blended in a natural manner. The material may be shaped to form stripes, lobes, spots and the like as well as to vary the translucence, opacity or color of different portions of the tooth.

The teeth may be removed from moulded unit 46 by a trimming operation and the individual teeth can then be subjected to polishing and the like if desired.

Two-Stage Process

55 In forming the teeth in two stages, I may employ mould parts 51 and 52 illustrated in Figures 7 and 8 respectively. These mould parts are similar to mould parts 19 and 23 other than the shape of the depressions 53 and 54. The mould parts 51 and 52 are adapted to form the body portion 55 of the tooth, which is the first stage in this particular instance. Since it is desired to have the relatively translucent enamel or veneer extend incisally beyond the body portion 55, it is necessary that the body portion be prevented from extending to the incisal portion of the teeth, and this is effected by providing an elevated lip 56 at the incisal portion of depression 53. The lingual surface forming depressions 54 in mould part 52 are provided with a mating recess or shelf 57 for receiving lip 56. Thus, when the mould parts are engaged, as illustrated in Figure 11, the resulting cavity 58 conforms to the body portion of the tooth. As illustrated in Figure 7,

the depressions 53 adapted to form the labial surface of the body portion 55 may be provided with grooves 59 which will result in an elevated stripe 60 on the moulded body portion, and this groove may be extended into lip 56, as indicated at 61, so that the resulting stripe on the body portion will extend incisally beyond the body portion proper, and in the finished tooth will appear through the relatively translucent enamel as a stripe extending into the enamel incisal portion. Also, lip 56 may be provided with arcuate concavities 62 so that the moulded body portion will terminate incisally in the form of rounded projections, which will appear through the enamel of the finished tooth in the form of lobes. The depth of the concavities which form these individual lobes may be varied in relation to each other so that effects caused by over or under development of dentine segments in natural teeth may be reproduced in artificial teeth. Mould parts 51 and 52 will be mounted in housings 18 and 22 and the mating surfaces of the mould parts will be engaged and the body material injected as described in the single stage process. The moulded unit indicated at 63 in Figure 9 is then removed from mould part 52 and the unit is cut to remove dotted portion 64 and provide individual bars 65 each having body portions 55 attached thereto. Bars 65 and the attached body portions are then disposed in channels 66 and depressions 67 provided in a mould part 68. Each depression 67 is a replica of a corresponding depression in mould part 52 except that the depression 67 is slightly deeper at the incisal area, as indicated at 70 in Figure 13, to allow enamel to flow under the incisal termination of the body portion and thereby insure more strength in the tooth as well as a closer simulation to natural teeth, and the depression 67 extends beyond the body portion incisally so that when mould part 19 of Figure 1 is engaged with mould part 68, a cavity is formed between the labial surface 55a of the body portion and the depression 27 for receiving the enamel or veneer. If a single injection machine is used, a desired number of moulded units 63 may first be made, and then the mould parts 51 and 52 are replaced by mould parts 68 and 19, the bars 65 and attached body portions are placed in mould part 68, as previously described, and the mould parts are brought into engagement. Enamel material is then injected into the veneer-forming cavities 69, the material flowing from nozzle 17 through a centrally disposed main gate 11, and smaller gates 12 to the individual veneer cavities 69.

The moulded unit indicated at 13 is then removed from mould part 68 and the individual teeth severed therefrom, as previously described.

It will be noted by reference to Figures 11 and 13 that the elevated stripe 60 formed on the labial surface of the body portion 55 extends into the veneer-forming cavity 69 and provides a thinned-out area in the veneer so that the stripe appears through the translucent veneer in contrasting color, as illustrated in Figure 10. In the same manner the lobe formations on the body portion 55 appear through the veneer in contrasting color to simulate markings frequently found in natural teeth.

Figures 16 and 17 illustrate a finished tooth wherein the veneer overlies the mesial and distal sides of the body portion, as indicated at 86, and the veneer may be extended any desired distance into the gingival area of the tooth. Also, the veneer overlies the lingual incisal surface of the

body portion, as indicated at 81, and thus an enamel veneer jacket is provided forming the incisal portion of the tooth and overlying the labial, mesial, distal and lingual surfaces of the body portion.

It is understood that the body portion 55 will be shaped by the mould parts 51 and 52 to provide space along the mesial and distal sides of the body portion for receiving the veneer material when it is desired to have the veneer extend along the mesial and distal sides of the tooth, as illustrated in Figure 16. The veneer-forming cavity 69, in this instance, will include the space intermediate the body portion 55 and the mesial and distal sides of depressions 27 provided in face forming mould part 19.

The enamel material is translucent relative to the material of the body portion 55, and the body material may be of the same composition as the enamel material with a coloring agent or opacifier added thereto. Also, a plastic material of one class may be used for the body portion and a plastic material of another class used for the enamel if the materials are compatible as to bonding or adhesive qualities. For example, acrylic material might be employed for the body portion and styrene material for the enamel. Prior to injecting the enamel material a solvent or cement may be applied to the surface 55a of the tooth body portion, or heat may be applied to the exposed surface 55a of the body portion just prior to injecting the enamel material.

Of course, organic or inorganic coloring material as described in connection with the one-stage process may be incorporated in the body portion, enamel portion, or both, to further simulate the appearance of natural teeth.

Although in the two-stage process described the body portion was first formed, it is understood that the enamel or veneer may be first formed and the body portion injected as the second stage. In first forming the enamel a mould part similar to mould part 19 of Figure 1 would be used in cooperation with a mould part having convex surfaces conforming to the contour of the lingual surface of the enamel, or individual auxiliary dies of the same shape as body portion 55 may be mounted in depressions 31 of mould part 28 of Figure 2. The use of these dies would reduce the number of mould parts required and they could be secured by a pin adapted to seat within holes 38 of depressions 31.

Third method

A third method of forming artificial teeth of plastic material having a translucent enamel veneer and a relatively opaque body portion is to separately mould the enamel and the body portion. Of course, this would require the use of four moulds. These two separately formed parts will then be securely united by painting or spraying a solvent or cement for the particular plastic material used over the lingual side of the enamel portion or the labial side of the body portion or both and quickly pressing the parts together in proper position. If one class of plastic material is used for the enamel and another class for the body portion a bonding agent compatible with both materials would be used.

It will be noted by reference to Figure 17 that a projection 82 formed of the same material as the body portion 55 of the tooth extends from the lingual surface thereof, and that the extent of this projection may be controlled as desired through the positioning of knock-out pins 81 dur-

ing the moulding of the body portion 55. These projections serve as anchoring means for attachment of the teeth to a denture base or the like.

In Figure 14, I have indicated a conventional mechanical anchorage 76 which may comprise a metallic pin having an enlarged head adapted to be embedded in the body portion during the moulding operation. The anchorage 76 may be disposed in the body forming depressions and supported on knock-out pins 37 so that body material may flow under the head portion and securely embed it in the body portion.

Although for purposes of illustration, I have shown mould parts adapted to concurrently mould twelve anterior teeth, or teeth portions, it is understood that any desired number of anterior or posterior tooth cavities or pockets may be provided in the mould parts or that an individual nozzle may inject tooth material concurrently into several sets of cooperating mould parts. It will now be apparent that teeth formed as described herein may be very rapidly produced, and that due to shaping of the tooth cavities to provide stripes, spots, lobes and the like, together with the fact that such a large variety of color material may be used, teeth closely simulating natural teeth in appearance may be provided.

Although I have shown and described preferred forms of my invention, I contemplate that numerous and extensive modifications may be made without departing from the spirit of my invention and the scope of the appended claims.

The invention is hereby claimed as follows:

1. The method of forming artificial teeth from plastic resins by injection moulding which comprises providing metal separable mould parts adapted to form a tooth cavity therebetween when engaged, the mould part adapted to form the lingual surface of the tooth having a port extending to said lingual moulding surface engaging said mould parts under high pressure, closing a portion of said port, injecting plastic resin material into the mould cavity under high pressure while heated to a flowable condition to concurrently mould and finish harden said material, separating the mould parts, whereby the

moulded tooth will be retained in the mould part provided with the port, and ejecting the moulded tooth by pressure exerted at the port, whereby an anchoring projection is formed on the lingual surface of the tooth by the material projected into the port during the moulding operation.

2. The method of forming artificial teeth from plastic resins by injection moulding which comprises providing separable metal mould parts having moulding surfaces adapted to form a tooth cavity therebetween when engaged, disposing solid pre-formed coloring material in one of said moulding surfaces adapted to retain its form at the hardening temperature of the plastic resin material, engaging said mould parts under high pressure, and then injecting the plastic resin material into the mould cavity under high pressure while heated to a flowable condition to concurrently mould and finish harden the plastic resin material and incorporate the coloring material therein.

3. The method of forming artificial teeth of the type comprising a relatively translucent veneer portion and a relatively opaque body portion from plastic resins by injection moulding, said method comprising the steps of providing a three-part metal mould, with two of said parts being adapted to form one portion of the tooth, engaging the two said mould parts under high pressure, injecting plastic resin material under high pressure and in flowable condition into said mould parts to concurrently mould and harden one portion of the tooth, separating the mould parts while retaining the moulded portion in one mould part, engaging the third mould part under high pressure with the mould part containing the moulded portion, whereby a cavity is formed intermediate the moulding surface of the third mould part and the exposed surface of the moulded portion, and then injecting plastic resin material of different composition from the first injected material under high pressure and in flowable condition to finish harden said portion of the tooth and concurrently completely mould the tooth and unite both tooth portions.

HENRY M. THORNTON.
